DESIGN FOR A BROOCH OR SIMILAR ARTICLE

John S. Suarez, Brooklyn, N. Y.

Application February 10, 1942, Serial No. 105,740

Term of patent 3½ years

To all whom it may concern:

Be it known that I, John S. Suarez, a citizen of the United States, residing in the Borough of Brooklyn, county of Kings, city and State of New York, have invented a new, original, and ornamental Design for a Brooch or Similar Article, of which the following is a specification, reference being had to the accompanying drawing, forming part thereof.

On the drawing,

Fig. 1 is a top plan view of a brooch or similar article embodying the invention; and

Fig. 2 is a front elevational view of the same.

I claim:

The ornamental design for a brooch or similar article, as shown.

JOHN S. SUAREZ.
